(57) **CLAIM**

The ornamental design for a cover rack for vehicle as shown and described.

DESCRIPTION

1. Cover rack for vehicle
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged

The broken lines in the reproductions depict portions of the cover rack for vehicle that form no part of the claimed design; figs. 1.9 and 1.10 are enlarged views of the portions shown by dash-dotted square and straight lines and number 1.9 in fig. 1.1 and dash-dotted square and straight lines and number 1.10 in fig. 1.2, respectively; the dash-dotted square

(Continued)

and straight lines in the reproductions represent boundaries for the enlarged views and form no part of the claimed design.

1 Claim, 10 Drawing Sheets
